DESIGN FOR A SHOE SOLE

William E. Kavenagh, Windsor, Vt., assignor to
Wingfoot Corporation, Akron, Ohio, a corpora-
tion of Delaware

Application October 26, 1946, Serial No. 134,273

Term of patent 14 years

(Cl. D7—5)

To all whom it may concern:

Be it known that I, William E. Kavenagh, a citizen of the United States, residing at Windsor, in the county of Windsor and State of Vermont, have invented a new, original, and ornamental Design for a Shoe Sole, of which the following is a specification, reference being had to the accompanying drawing, forming part thereof.

Fig. 1 is a plan view of a shoe sole showing my new design; and

Fig. 2 is a side elevational view looking in the direction of the arrows 2—2 on Fig. 1.

I claim:

The ornamental design for a shoe sole, as shown.

WILLIAM E. KAVENAGH.
